Primary Examiner — Brett Miller*Assistant Examiner* — Jessica M Gebhart(74) *Attorney, Agent, or Firm* — Crowell & Moring LLP(57) **CLAIM**

The ornamental design for a holding chamber, as shown and described.

DESCRIPTION

FIG. 1 is a perspective view of a holding chamber; FIG. 2 is a front view of the holding chamber shown in FIG. 1;

FIG. 3 is a rear view of the holding chamber shown in FIG. 1;

FIG. 4 is top view of the holding chamber shown in FIG. 1; FIG. 5 is a right side view of the holding chamber shown in FIG. 1;

FIG. 6 is a left side view of the holding chamber shown in FIG. 1; and,

FIG. 7 is a bottom view of the holding chamber shown in FIG. 1.

The broken lines in the drawings depict portions of the article that form no part of the claimed design.

1 Claim, 4 Drawing Sheets# US D1,010,101 S
